J. D. SCHAKEL

LEVELING ATTACHMENT FOR PUSH BUTTON ELEVATORS

Filed August 30, 1924

Inventor
Jacob D. Schakel
by May A. Zabel Atty.

UNITED STATES PATENT OFFICE.

JACOB D. SCHAKEL, OF CHICAGO, ILLINOIS, ASSIGNOR TO ELEVATOR COMPANY OF AMERICA, OF CHICAGO, ILLINOIS, A CORPORATION OF ILLINOIS.

LEVELING ATTACHMENT FOR PUSH-BUTTON ELEVATORS.

Application filed August 30, 1924. Serial No. 735,161.

My invention relates to switches, and more particularly to a leveling attachment for push button elevator switches.

It is a purpose of my invention to provide a switching device for use in controlling the movements of a body that moves in a fixed path such as an elevator moving up and down in a shaft. In certain cases it is very desirable to have the moving body such as 5 the elevator remain at a predetermined point or station for an extended period of time and to also cause said body to stop precisely at said station when a stop is to be made thereat. This is particularly desirable in the case of elevators that are used 10 for the purpose of hauling freight, where a wheeled vehicle is to be moved from a fixed level such as a floor on to a moving platform such as an elevator or off the elevator platform on to the floor. In such cases it is very 15 desirable that the elevator and the floor lie in the same plane or that the elevator is exactly level with the floor.

It is a purpose of my invention to provide 20 new and improved means associated with a moving body such as an elevator for accomplishing this purpose whereby substantially no changes are necessary in the equipment of the elevator and the leveling device is 25 merely in the form of an attachment to the previously provided mechanism. Electric elevators are ordinarily operated by a switch mechanism in the car that is to be actuated manually by the operator to cause 30 the car to move in either direction or to stop as desired. The mechanism in the car is 35 ordinarily known as a push button switch and is associated with certain controlling devices that are located at a remote point 40 from the car, but near the motor for operating the same so that actuation of the push button switch will cause operation of the controlling means in a proper manner to move the car in the desired direction or to 45 automatically stop the car when the power is shut off. The standard devices for this purpose are not involved in the present invention and are not altered in any way in carrying out the purpose of this invention.

50 It is a purpose of my invention to provide suitable switch closing mechanism that is actuated by the movement of the car or other movable body to operate the switch

ordinarily provided in the ordinary manner, the operation thereof operating the motor in the usual manner through the usual controller provided in connection with the switch adjoining the motor.

More particularly it is a purpose of my invention to provide a switch for operating 55 an elevator or similar moving body that moves in a fixed path in opposite directions comprising a pair of push buttons, one of which closes a contact for moving the car in one direction and the other of which closes 60 the contact for moving the car in the opposite direction, said mechanism being provided in addition with mechanical means 65 for actuating said contacts, which mechanical means are controlled by the movement of 70 the car. The push buttons are connected up with suitable contacts on a standard controller and the controller is provided with suitable mechanism whereby the two circuits 75 for operating the motor in opposite directions cannot be simultaneously closed, this being a standard construction that is well-known in the art and is not involved in the present invention.

In the embodiment of the invention 80 shown in the drawings, the push button switching device comprises a pair of push button members each actuating a movable contact member which is adapted to bridge 85 a pair of contacts to close a circuit for moving the car in opposite directions. The movable contact members are provided with means for normally holding the same in a position such that the movable contact is 90 in open circuit position, it being necessary 95 to constantly push the button to hold the switch associated therewith in closed position. The movable contact of each switch is preferably provided with an extension having a slot therein in which the end of a lever engages that is normally held in such a position that the same will exert no pull 100 on the extension of the contact member, but which is provided with means engaging cams or other similar members in the path of the movement of the car to move the movable switch member associated therewith to circuit closing position.

Other objects and advantages of the invention will appear as the description of the 105 accompanying drawings proceeds. How-

ever, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

10 Fig. 1 is a view partly in vertical section and partly in elevation of my improved mechanism in position on a moving body such as an elevator car; and

15 Fig. 2 is a face view on a reduced scale of the mechanical means for moving the switch members.

Referring in detail to the drawings, my improved switch mechanism comprises a base member 10, which is mounted on any suitable portion of a movable body such as an elevator car 11, said base member being provided with a cover 12 secured thereto in any suitable manner. Mounted on said base member 10 is a block of insulating material 13 and between said block of insulating material 13 and said base member 10 is a sheet of insulating material 14. The member 13 is preferably made of slate and the member 14 of mica, although different material may be used if desired. Mounted on said member 13 are members of conducting material 15, 16, 17 and 18. Each of said members 15, 16, 17 and 18 are provided with an ear 19 having a screw-threaded opening for receiving the binding screw 20 by means of which the conductors 21, 22, 23 and 24 are secured respectively to said members 15, 16, 17 and 18. Each of said members of conducting material is also provided with a boss 25, 40 which bosses are located in recesses 26 in the insulating member 13. Screws 27 pass through suitable openings in said insulating member and have screw-threaded engagement with the bosses 25 to secure the conducting members 15, 16, 17 and 18 in position, the heads of said screws being countersunk in the openings 28 as will be clear from Fig. 1, the mica sheet 14 preventing engagement of said heads with the member 10. 50 The member 13 is further provided with openings 29 into which the screws 20 extend, the screws 20 being much shorter than the thickness of the material 13, thus preventing engagement of the binding screws 55 with the mica sheet 14. The conductors 21 and 22 lead to a set of contacts on the controller as is well-known for closing the circuit for moving the elevator car in one direction such as for example, downwardly, 60 while the conductors 23 and 24 lead to a similar pair of contacts on the controller for moving the elevator car in the opposite direction, or upwardly. Each of the conducting members is provided with a socket portion 30 in which a slidable contact member

is located. The contact members associated with the members 15, 16, 17 and 18 being designated respectively by the numerals 31, 32, 33 and 34.

Each of said members 31, 32, 33 and 34 is provided with a pair of laterally projecting pins 35 that are adapted to move in the slots 36 in the conducting members to thus limit the movement of the members 31, 32, 33 and 34 in both directions. A coil spring 37 is mounted in each of the socket members 30 between the contacts 31, 32, 33 and 34 and the bottom of the socket, thus, providing a spring projected contact associated with each of the conductors leading to the switch.

The spring projected contacts 31 and 32 associated with the conductors 21 and 22 are adapted to be bridged by a movable contact member or bridging member 38 and the contacts 33 and 34 associated with the conductors 23 and 24 are adapted to be bridged by a similar contact member 39. The contact member 38 is mounted on a rod-like member 40, said contact 38 being mounted between a washer 41 of insulating material having a hub or sleeve-like portion 42 thereon passing through a central opening in the member 38 and a washer 43 of insulating material, said washers 41 and 43 being secured in position on the member 40 and being clamped together to clamp the member 38 between them by means of a screw 44, a washer 45 of metal being provided between the insulating member 41 and the head of the screw 44. The member 38 is made in the form of a disk-like member of any suitable good conducting material such as copper and the members 31 and 32 are preferably made of carbon, although obviously either of these members could be made of any other suitable conducting material. A compression spring 46 is located between the boss 48 provided on the insulating member 10 and a washer 49 provided on the member 40 between the insulating member 43 and the end 110 of the member 40, said washer being provided to prevent any damage of the insulating member 43 by the spring 46.

A push button 50 is provided having an enlarged portion 51 which is provided with a recess 52 to accommodate the head of the screw 44, said enlarged portion 51 engaging with the member 41 to move the contact 38 into engagement with the contacts 31 and 32 when the button 50 is moved inwardly from the position shown in Fig. 1. The button 50 is slidably mounted in a hollow boss 53 provided on the cover 12 and the end thereof is normally located inwardly from the outer end of the boss 53. Accordingly, it will be seen that the push button cannot be accidentally moved to close the circuit by coming into accidental engagement therewith, but the finger must be inserted in the boss 53, which has an opening of sufficient size to 130

permit insertion of the operator's finger, to 5 depress the button 50 to close the circuit for moving the elevator car downwardly. The enlargement 51 engaging with the inner side of the cover 12 prevents projection of the button 50 beyond the member 53. Normally, the parts are in the position shown in Fig. 1 due to the spring pressure exerted by the coil spring 46. The button 50 is independent 10 of the member 40 merely engaging therewith due to the action of the spring 46 and due to the inward movement of the button upon the same being pushed inwardly, but is not carried with the member 40 upon inward movement of said member 40.

The member 40 projects outwardly beyond the member 11 in an opposite direction to the switch casing and parts contained therein and is provided on the outer end 20 thereof with an enlargement 54 that is provided with a longitudinal slot 55. A bracket member 56 is mounted in any suitable manner on the movable body or elevator car 11 and is provided with bearings 57 for the 25 pivot pin 58 of a bell crank lever having an arm 59, the end portion of which is engaged in the slot 55 and with an arm 60 having a pivot pin 61 mounted in the bifurcated end 62, thereof, a roller 63 being 30 mounted on said pivot pin 61, said roller 63 being adapted to engage with a cam member 64. The bell crank lever is normally held in the position shown in Fig. 1 by means of the compression spring 65 that is 35 mounted between a boss 66 on the arm 60 of the lever and a boss 67 provided on the enlargement 68 on the bracket 56. The normal position of the bell crank lever can be adjusted by means of an adjusting screw 69 40 screw-threadedly mounted in the arm 59 of the lever, said adjusting screw being provided with a lock nut 70 for locking the same in adjusted position and being adapted to engage with the projection 71 on the bearing member 66 when the parts are in the 45 position shown in Fig. 1.

When the roller 63 engages with the cam 64, the arm 60 of the pivot crank lever is thrown in a clockwise direction and the arm 59 is similarly moved in a clockwise direction, thus moving the member 40 to the left in Fig. 1, and moving the contact member 38 into engagement with the contacts 31 and 32. The cam 64 is adjustably mounted in 55 a fixed position in the elevator shaft or in the path of movement of the movable body in case the device is used on other movable bodies than elevators. The adjustable mounting may be of any form, being shown 60 in the drawing as comprising bolt-like clamping means 72 which pass through the slots 73 in the cam 64, the cam 64 being stationary and being positioned above the point 65 which the roller 63 will reach when the elevator car floor is level with the floor of the building. It is obvious that if the elevator car floor is above the floor of the building, the adjustment of the cam can be made such that the roller 63 will immediately engage with the cam 64 causing the contact member 38 to be moved to circuit closing position which would cause the elevator car to move downwardly. As soon as the roller 63 is moved to the position shown in Fig. 1 or after the same has left the cam 64, the spring 65 will restore the lever to its normal position and the spring 46 will then move the contact 38 to open circuit position, whereupon the car or other movable body will be stopped in the usual manner. If the button 50 is depressed when the floor or station at which the cam 64 is located is being passed, the roller 63 will engage with the cam 64 but the action of the bell crank lever will produce no effect on the switch mechanism due to the fact that the arm 59 will merely move from near the inner end of the slot 55 to the outer end thereof.

The contact member 39 is mounted on the rod-like member 74 by means of the insulating members 41 and 43 and the screw 44 in a similar manner to which the contact 38 is mounted on the member 40. A coil spring 46 mounted between the washer 49 and the boss 48 is also provided for projecting the member 39 in a direction away from the contacts 33 and 34, the construction being a duplicate of the parts used in connection with the member 40. A push button 75 mounted in the hollow boss 76 on the cover member 12 of the switch mechanism is provided for moving the contact member 39 into engagement with the contacts 33 and 34 and is provided with an enlargement 77 engaging with the insulating member 41 provided on the member 74 and is further provided with a recess 78 to accommodate the head of the screw 49, the operation of said push button 75 being substantially the same as that of the push button 50, the same being mounted so as not to project beyond the casing for the same reason as is the case with the push button 50.

The push button 75, when the same is held in depressed position, closes the circuit through the contacts 33, 34 and 39 which in a well-known manner operates the usual controller so as to complete circuits whereby the elevator car or other movable body is moved in the opposite direction to that when it is moved when the push button 50 is depressed. As previously explained, the standard controller used for two push button elevators is provided with suitable means for preventing both circuits for moving the car or other movable body in opposite directions from being closed at the same time. In other words, if the button 75 has been depressed to close the circuit to move the elevator car upwardly, a depression of the but-

ton 50 with the button 75 remaining depressed will have no effect on the operation of the elevator or other movable body 11.

The rearwardly or outwardly projecting end of the member 74 is provided with an enlargement 79 having a longitudinally extending slot 80 therein in which engages the arm 81 of the bell crank lever having an arm 82 provided with a roller 83 that is adapted to engage with the cam 84 which is adjustable in a similar manner to the cam 64, the adjustable mounting being indicated by the same numerals as in the case of the cam 64. The bell crank member is pivotally mounted on the bracket 85 in a similar manner to that in which the bell crank lever previously described is mounted on the bracket 56. An adjusting screw 69 being also provided on this bell crank lever for adjusting the normal position thereof and a coil spring 65 being provided for projecting the roller 83 outwardly as is the case with the roller 3. The corresponding parts of the two bell crank levers except the arms and rollers are indicated by the same numerals, as these parts are exactly the same. Different numerals are used for the arms and rollers, as it more clearly distinguishes between the same in referring to the operation of the two switches.

It will be noted upon reference to Fig. 2 that due to the fact that the rollers 63 and 83 are offset from the arms 59 and 81 respectively of the bell crank levers, the rollers will lie in different positions and accordingly the cams 64 and 84 will lie in a different path and the roller 63 will not engage with the cam 84 as it moves past the same, nor will the roller 83 engage with the cam 64 as it moves past said cam. It is, of course, obvious that any number of cams 64 and 84 may be provided depending on the number of floors or stations at which the movable body or car is to stop and it will also be seen that if all of the cams 64 and all of the cams 84 are aligned respectively, the roller 63 will only actuate the switch when it passes the cams 64 and the roller 83 will only actuate the switch when the same passes the cams 84.

The operation of the bell crank lever comprising the members 81 and 82 when the roller 83 engages with the cam 84 is obvious, such engagement causing the closing of the switch due to the engagement of the member 39 with the members 33 and 34. It will be evident that the spacing of the members 64 and 84 can be such that a very accurate stopping of the movable body carrying the switch mechanism described can be obtained. The cams can be adjusted to a small fraction of an inch so that a slight movement of the member 11 downwardly out of its desired position in Fig. 1 will cause the roller 83 to engage with the cam 84 and close the switch 39 which controls the

upward movement of the car immediately restoring the car to its desired position level with the floor. Similarly, an upward movement of the body or car 11 due to lightening of the load thereon which would cause the roller 63 to engage with the cam 64 will cause the actuation of the bell crank lever associated with the roller 63 to move the contact 38 into circuit closing position, thus, immediately causing the proper circuits to be closed whereby the car 11 will again be caused to move downwardly until the roller 63 has left the cam 64 whereupon the circuit is again open due to the action of the springs 46 and 65. From the above explanation, it will also be evident that when it is not desired to stop at a floor, the action of the two bell crank switch operating members will have no effect on the operation of the car as long as one or the other of the push buttons 50 or 75 is held in circuit closing position. However, if the one that has been depressed for moving the car either upwardly or downwardly is released within a distance of the floor such that it is within the range of either the cam 64 or 84, the proper switch will be either held in closed position or moved to closed position to move the car in the direction toward the floor until the same is level with the floor.

Having thus described my invention, what I desire to claim and secure by United States Letters Patent is:

1. A car-leveling system of the character described comprising a switch having a movable contact member adapted to control the movement of a car, an operating member for manually moving said contact member into circuit closing position and a mechanically operated member controlled by the position of said car for moving said contact member into circuit closing position independently of said manual operating member.

2. A car-leveling system of the character described comprising a switch having a movable contact member adapted to control the movement of a car, an operating member for manually moving said contact member into circuit closing position and a mechanically operated member controlled by the position of said car for moving said contact member into circuit closing position, each of said members for moving said contact to circuit closing position being independent of the other of said members.

3. A car-leveling system of the character described comprising a pair of switches each having a movable contact member adapted to control the movement of a car, an operating member for manually moving said contact member into circuit closing position and a pair of mechanically operated members controlled by the position of said car operable independently of said manually operated members for moving said contact

member into circuit closing position, said mechanically operated members being so mounted that one of said members is out of contact closing position when the other member is in contact closing position.

4. In a car-leveling system of the character described, the combination with a movable car body of means for controlling the movement of said body comprising a switch having a movable contact element adapted to control the movement of the car, manually operable means for moving said contact element into circuit closing position and means independent of said manually operable means controlled by the movement of said body for moving said contact element into circuit closing position.

5. In a car-leveling system of the character described, the combination with a movable car body of means for controlling the movement of said body comprising a switch having a movable contact element adapted to control the movement of the car, means normally urging said contact element toward open circuit position, manually operable means for moving said contact element into circuit closing position and means independent of said manually operable means controlled by the movement of said body for moving said contact element into circuit closing position.

6. In a car-leveling system of the character described, the combination with a movable car body of means for controlling the movement of said body comprising a switch having a movable contact element adapted to control the movement of the car, means normally urging said contact element toward open circuit position, manually operable means for moving said contact element into circuit closing position and means independent of said manually operable means controlled by the movement of said body for moving said contact element into and holding the same in circuit closing position.

7. In a car-leveling system of the character described, the combination with a movable car body of means for controlling the movement of said body comprising a switch having a movable contact element adapted to control the movement of the car, means normally urging said contact element toward open circuit position, manually operable means for moving said contact element into circuit closing position and means independent of said manually operable means controlled by the movement of said body for moving said contact element into and holding the same in circuit closing position at predetermined points in the path of movement of said body.

8. In a car leveling system of the character described, the combination with a car body movable in a predetermined path, of means for controlling the movement of said

body comprising a switch controlling the movement of said body in one direction having a movable contact element adapted to control the movement of the car, manually operable means for moving said contact element into circuit closing position, means controlled by the movement of said body for moving said contact element into circuit closing position, a switch controlling the movement of said body in the opposite direction having a movable contact element, manually operable means for moving said last mentioned element into circuit closing position, and means controlled by the movement of said body for moving said last mentioned contact into circuit closing position.

9. In a car leveling system of the character described the combination with a car body movable in a predetermined path, of means for controlling the movement of said body comprising a switch controlling the movement of said body in one direction having a movable contact element adapted to control the movement of the car, manually operable means for moving said contact element into circuit closing position, means controlled by the movement of said body for moving said contact element into circuit closing position, a switch controlling the movement of said body in the opposite direction having a movable contact element, manually operable means for moving said last mentioned element into circuit closing position, and means controlled by the movement of said body for moving said last mentioned contact into circuit closing position, said means controlled by the movement of said body being mounted so that one of said means is in open circuit position when the other of said means is in circuit closing position.

10. In a car leveling system of the character described, the combination with a car body movable in a predetermined path past a station, of means for controlling the movement of said body comprising a pair of switches controlling the movement of said body in opposite directions; each switch having a movable contact element adapted to control the movement of the car, means for manually moving said contact element into circuit closing position and means for moving said contact element into circuit closing position controlled by the movement of said body; the means controlled by the movement of the body being so mounted that both of said means are out of circuit closing position when said body is aligned with said station.

11. In a car-leveling system of the character described the combination with a car body movable in a predetermined path past a station, of means for controlling the movement of said body comprising a pair of switches controlling the movement of said

body in opposite directions; each switch having a movable contact element adapted to control the movement of the car, means for manually moving said contact element into circuit closing position and means for moving said contact element into circuit closing position controlled by the movement of said body; the means controlled by the movement of the body being so mounted that both of said means are out of circuit closing position when said body is aligned with said station, and the one of said last mentioned means controlling movement of the body toward said station is moved to circuit closing position upon movement of said body away from said station in either direction.

12. A car-leveling system of the character described comprising a switch having a pair of contacts adapted to control the movement of the car, a member movable into bridging relation to said contacts, means normally holding said member spaced from said contacts, a push button for moving said member into bridging relation to said contacts and a mechanically operated member controlled by the position of said car for moving said bridging member into bridging relation to said contacts, said bridging member and mechanically operated member being loosely connected together.

13. A car-leveling system of the character described comprising a switch having a pair of contacts adapted to control the movement of the car, a member movable into bridging relation to said contacts, means normally holding said member spaced from said contacts, a push button for moving said member into bridging relation to said contacts, a lever for moving said member into contact bridging position and means controlled by the position of said car for mechanically actuating said lever, said lever being loosely connected with said bridging member.

14. A car-leveling system of the character described comprising a switch having a pair of contacts adapted to control the movement of the car, a member movable into bridging relation to said contacts, means normally holding said member spaced from said contacts, a push button for moving said member into bridging relation to said contacts, and an extension on said bridging member having a slot therein, a lever engaging in said slot for moving said member controlled by the position of said car into contact bridging position and means for mechanically actuating said lever.

15. In a car-leveling system of the character described the combination with a car body movable in a predetermined path past a station, of means for controlling the movement of said body comprising a pair of switches controlling the movement of said body in opposite directions, each switch hav-

ing a movable contact element, means for manually moving said contact element into circuit closing position and means for moving said contact element into circuit closing position controlled by the movement of said body, the means controlled by the movement of the body comprising a pair of cams, and levers having rollers each engaging one of said cams, each lever operating one of said switches.

16. In a car-leveling system of the character described the combination with a car body movable in a predetermined path past a station, of means for controlling the movement of said body comprising a pair of switches controlling the movement of said body in opposite directions, each switch having a movable contact element, means for manually moving said contact element into circuit closing position and means for moving said contact element into circuit closing position controlled by the movement of said body, the means controlled by the movement of the body comprising a pair of spaced cams fixed in said path, one spaced in one direction of movement of said body from said station and the other spaced in the opposite direction of movement of said body therefrom, and a member associated with each of said switches and co-operating each with one of said cams to close its switch when in engagement therewith.

17. In a car-leveling system of the character described the combination with a car body movable in a predetermined path past a station, of means for controlling the movement of said body comprising a pair of switches controlling the movement of said body in opposite directions, each switch having a movable contact element, means for manually moving said contact element into circuit closing position and means for moving said contact element into circuit closing position controlled by the movement of said body, the means controlled by the movement of the body comprising a pair of spaced cams fixed in said path, one spaced in one direction of movement of said body from said station and the other spaced in the opposite direction of movement of said body therefrom, and a member associated with each of said switches and co-operating each with one of said cams to close its switch when in engagement therewith, said cams being so spaced that both said members are out of engagement therewith when the body is in alignment with the station and the switch closing member associated with the switch controlling movement of the body toward said station engages its cam when said body is out of alignment with said station.

In witness whereof, I hereunto subscribe my name this 8th day of August, A. D. 1924.

JACOB D. SCHAKEL.
